JAMES H. RAMBO, OF MINNEAPOLIS, MINNESOTA, ASSIGNOR TO MINNEAPOLIS KNITTING WORKS, OF MINNEAPOLIS, MINNESOTA, A CORPORATION OF MINNESOTA.

CHILD'S SLEEPING GARMENT.

Application filed September 8, 1925. Serial No. 55,117.

My invention relates to child's sleeping garment and particularly to the foot portion thereof and the object of the invention is to provide a foot piece formed and stitched 5 in such a way that danger of pulling or ripping the seams usually resulting from the kicking of the sleeping child will be practically eliminated. A further object is to provide a sleeping garment having foot portions or pieces in which small waste pieces 10 of the knitted fabric may be used. Other objects of the invention will appear from the following detail description. In the accompanying drawings forming part of this specification:

Figure 1 is a perspective view showing the appearance of the garment on the child;

Figure 2 is a view of the outer side of one of the foot portions;

Figure 3 is a corresponding view of the inner side;

Figure 4 is a rear view; and

Figure 5 is a bottom view.

In the drawings I have indicated the garment as a whole by reference numeral 2, the foot portions composed of knitted fabric comprising an upper portion 3, a bottom or sole portion 4, and an intermediate gore or heel portion 5. A seam 6 unites the edge 25 of the sole portion 4 to the parts 3 and 5 and a similar seam 7 connects the upper edge of the gore 5 with the adjacent edge of the part 3. I have found in the use of these garments that where a vertical seam is provided at the heel portion there is a tendency 30 to pull or stretch it in the movement of the child's legs resulting in a ripping or tearing of the stitches and a consequent hole in the garment at this point. To eliminate this difficulty I provide the gore 5 with the wales 35 running horizontally around the heel of the garment so that in the kicking movement of the child's legs the gore will stretch transversely and relieve the stitches 6 and 7 of strain or pull thereon which might otherwise result in tearing the stitches apart and making a hole in the garment. This gore also 40 is adapted to stretch in walking or as the foot is bent in act of walking. Part 4 comprises an oval piece that is stitched to the gore and the lower edge of the upper 3 and forms in effect the sole of the foot piece. 45 When these sole pieces are worn out they

may be removed and new pieces substituted therefor and the necessity of throwing away 55 the entire foot piece of the garment is thereby eliminated. I am therefore able with this construction of foot piece to provide a sleeping garment of comparatively simple inexpensive construction which will be more durable than the usual garment of this kind 60 and when worn can be readily removed with comparatively little expense.

The form of foot shown and described herein for the sleeping garment provides 65 ample room over the instep, avoiding tightness and preventing the pulling or drawing of the seams between the pieces of the foot.

I claim as my invention:

1. A garment of the class described in- 70 cluding legs, and a foot portion for each leg, each foot portion comprising an upper formed by the lower portion of the leg, a sole, and a stretchable counter extending forwardly to a point adjacent the toe, and 75 stitched to upper and sole.

2. A sleeping garment including leg and 80 foot portions each foot portion comprising an upper formed by the lower portion of the leg, a counter of knitted fabric connected by its upper edge with the upper and extending forwardly to a point adjacent the toe, a sole connected to upper and counter, said counter having its wales horizontally arranged.

3. A child's sleeping garment including 85 legs each leg having a foot comprising an upper as a continuation of the leg portion, a sole piece stitched only at its forward portion to said upper, a counter, stitched to upper and sole piece and extending forwardly to a point adjacent the toe, the sole and counter being of knitted fabric.

4. A child's sleeping garment including 90 legs each leg having a foot comprising an upper as a continuation of the leg portion, a sole piece stitched only at its forward portion to said upper, a counter, stitched to upper and sole piece and extending forwardly to a point adjacent the toe, the sole and 95 counter being of knitted fabric and the wales of said counter being arranged horizontally.

In witness whereof, I have hereunto set my hand this 29th day of August, 1925.

JAMES H. RAMBO.
